COMPOSING MACHINE

Pierre Jean-Baptiste Astier, Paris, France

Application March 22, 1957, Serial No. 647,907

Claims priority, application France October 17, 1956

2 Claims. (Cl. 164—112)

The present invention relates to improvements relating to composing machines, for example, machines known on the market under the names of "Linotype," "Intertype," "Italtype," etc.

The method is known of automatically operating a composing machine from a tape, made of paper for example, punched according to a special code. This paper tape is punched in an apparatus independent from the composing machine, comprising a keyboard whose keys are arranged in a manner like the keys of an ordinary typewriter. To the applicants knowledge, no machine exists for punching the paper tape of which the keyboard is an integral reproduction of the keyboard of the composing machine itself.

Existing punching apparatuses possess an obvious disadvantage owing to the fact that the composing machine operator, being accustomed to the arrangement of the keys of his keyboard, is obliged to become acquainted with the keyboard of the paper tape punching machine. Otherwise the services of a typist have to be obtained, who is acquainted with the keyboard of an ordinary typewriter, which implies that two operators are required.

The present invention obviates these disadvantages and provides a keyboard of the type existing on a composing machine capable of punching a paper tape and at the same time playing its usual part in the composing machine. The improved keyboard according to the invention can also be utilized independently from the composing machine itself; owing to the conventional arrangements of its keys, it is not necessary to employ an operator other than the one already conversant with the composing machine.

According to another object of the invention, the conventional keyboard of a composing machine comprises additional members working in such manner that when a key is depressed by the operator, punching occurs according to a given code, on the tape, and a matrix is released from the magazine, which occurs in the conventional manner.

The chief advantages of the invention lie in the following facts: the working speed on the improved keyboard according to the invention is at least equal to that which it is possible to reach on the perforator keyboard of the type known at present.

If work is effected with a 7-hole code and with a keyboard according to the invention used as perforator only, independently from the composing machine, there is a possibility of gaining in speed by the elimination of the keys corresponding to shift and unshift.

The signal bringing about the rise of the assembling elevator is obtained on the paper tape according to a suitable code.

The keys of the keyboard are very sensitive and the operator acts on these keys in the same manner as he would on the keyboard of the composing machine itself.

The possibility of utilizing the spare magazines and any additional machine control member.

2

Recording on a paper tape during the normal running of the composing machine.

The possibility of checking the composition on the notches of the matrices.

Other advantages and features of the invention will be more clearly brought out by the ensuing description read in conjunction with the accompanying drawings, in which:

Figure 1 is a perspective view of one of the keys of the keyboard of a composing machine co-operating with the perforator according to the invention.

Figure 2 is a partial plan view corresponding to Fig. 1.

Figure 3 is an explanatory diagram of the movement of one of the members of Figure 1.

Figures 4a, 4b are elevational views of the counterweights of a conventional keyboard of a composing machine, these counterweights being altered so as to be applicable to the improved keyboard according to the invention, said counterweights being shown in two different positions.

Figures 5 and 6 are alternative embodiments of members of Figure 2.

Figure 7 is a diagrammatical view in perspective of the control circuit of the electro-magnet of Figure 1, called "synchronization circuit."

With reference to these drawings, Figure 1 shows in perspective, a key of a conventional keyboard of a composing machine co-operating with the perforator according to the invention. The references A designate the conventional counterweights or so called key bars that are already found on a conventional keyboard and which are actuated by the lever arms 416 hinged at 428 and connected to each key 417 of the keyboard. On a conventional keyboard comprising 90 keys, these counterweights number 91 i.e. 90 plus one counterweight corresponding to space bar. These counterweights A are notched or banked as usual at B (key side); moreover, on the opposite side to these notches or banks B, they comprise a series of notches C, being for example seven in number. This notching differs from one counterweight to another.

It is pointed out that the shape of these notches C, being different from one key to another, enables, as will be seen hereinafter, a special perforation to be obtained on a paper tape according to a code corresponding to each key under consideration.

Opposite to each notch C of the counterweights A there is a series of rods or bars (seven in number in the drawings) so mounted as to effect the oscillating movement shown in Figure 3. At the top part of this series of rods 1, a rod 1a is provided, and at the lower part of said series of rods 1, another rod 1b (not seen in the drawing) is also provided.

In Figure 3, O1, O2, O3, O4 show the hinging points having the same reference numerals in Figure 1; O1—O2, O3—O4 indicate the connections between these hinging points. Each bar 1 may thus make an oscillating movement shown by the arrows f₁ and f₂. It will easily be understood that if a part 3a (shown in dotted lines in Figure 3) abuts at any point along the bar 1, the oscillating movement of this bar will be prevented. Only the bars 1a and 1b can freely pivot without hindrance at any time of their displacement. This displacement takes place in the same way as that of the bars 1. The bars 1a and 1b only make the end perforations on a tape, these end perforations serving to guide the tape in its feeding system.

The description given below concerns the actuation of one or more rods 1 including the rods 1a and 1b and the perforation of a paper tape P.

Each rod or bar 1 is urged by a spring 2 in the direction of the arrow F1. Moreover, each of these rods 1 is extended by an arm 7 hinged at 8 and urged by a spring

9 (Fig. 2) in the direction of the arrow F_a ; each of these arms 7 is capable of acting through the intermediary of a shoulder 10 on a ratchet device 11 rotatably mounted about 12 and acting against a spring 13. The end of each arm 7 is capable of acting on rollers 14, 15, 16, and 17 mounted on a segment gear 18 mounted on a shaft 18a, said gear being adapted to mesh with a toothed wheel 19. The operation of this gear system 18-19 is described below.

Each of the rods 1, in its initial position, abuts against the end of a flap 20, hinged at 21, the side 23 of this flap abutting against a shoulder 24 of a part 25 hinged at 26 and capable of being attracted by an electro-magnet E1. The flap 20 is moreover hingedly connected by a bar 20a to a second flap 27 hinged at 28 and 29 whose function will be explained below. The above mentioned device as a unit is capable of acting on a rod 30 guided at 31 and 32 acting by its lower end on a punch 33 acting on the tape moving in the slot 34 of the device 35 guiding the tape. The rod 30 always acts on a lever system generally designated by the reference numeral 36 acting against a spring 37, this device 36 also serving to move the tape forward. This feed device may be of any conventional type such as a pawl and ratchet wheel device (35a).

The device described above operates in the following manner:

When a key of the keyboard of the composing machine is depressed, the electro-magnet E1 is excited as will be seen below. The part 25 is attracted in the direction of the arrow F_2 and the bars 1 corresponding to the key depressed, move in the direction of the arrow F_1 being urged by their spring 2 provided that these bars are opposite a notch C of the counterweight A. At the time of this movement the flap 20 pivots about 21 in the direction of the arrow F_3 , its side 23 no longer abutting on the shoulder 24; the arm 7, through the intermediary of its shoulder 10, acts on the latch 11 in the direction of the arrow F_4 , said latch abutting initially on the roller 16; by continuing its movement, the arm 7 acts on the roller 14 and compels the corresponding gear or gears 18 loosely mounted on their shaft 18a to rotate in the direction of the arrow F_5 thus compelling the segment S1 to mesh with the gear 19 which constantly rotates about the shaft 19a; the rotatory movement of this shaft being derived from any suitable device (not shown) (independent motor, power take-off from the composing machine itself, etc.).

When the gear 18 rotates in the direction of the arrow F_5 , said rotation being obtained from 19, the roller 15 50 strikes the rod 30, and thus causes the punching of the tape by means of the punch or punches 33.

Moreover, the roller 14 acts on the flap 27 which, during the pivoting of the flap 20 in the direction of the arrow F_3 , has moved in the direction of the arrow F_6 and restores this flap to its initial position. In returning to its initial position, the flap 20 brings the rod or rods 1 also into their initial position as well as the latch 11; each corresponding gear 18 has, during these displacements, made a quarter turn; on the other hand, the electro-magnet E1 being de-energized as will be hereinafter described, the part 25 has regained its initial position and the system is able to operate afresh.

It should be mentioned that the assembly 19, 18 can be formed by a friction system, of the current type such as is shown in Figure 5, the surfaces of 18 and 19 being made of suitable materials. This assembly may also be formed as in the case of Figure 6 by toothed segments of current type for 18 and by a gear 19 mounted on a rubber ring 19b for example.

The preferred form of embodiment of the invention is that shown in Figure 2 in which each gear 18 is a flexible gear obtained by cutting out circular slots in a circular plate, from the periphery thereof, so as to form resilient segments.

The electro-magnetic control of the device described above with a view to synchronising the operation of the machine, is shown in Figure 7; in this figure there has been shown one of the counterweights A co-operating with a key (not shown) of the composing machine, each of these counterweights A being adapted to act directly on a flap 38 which can pivot about a shaft 39; a counterweight 40 which is, for example, adjustable along a rod 40a is provided for balancing said flap. Moreover, this flap comprises two conductor blades 41 and 42 co-operating with two electric contacts 43 and 44. The contact 43 is connected to one of the terminals A_1 of a source of current supply; the blade 42 is connected to the same terminal A_1 . The contact 44 is connected to a contact 45 placed opposite a contact 46 connected to the electro-magnet E1. This contact 46 is carried by a lever arm 47 hinged at 48, urged by a spring 49 in the direction of F_b and carrying a pawl 50 at its end impelled by a spring 51 and co-operating with a ratchet wheel 52 which can be rotatably driven by means of an electro-magnetic clutch 53 (shown diagrammatically), for example, by a worm-gear system 54-55 (the worm being continuously rotated). The electro-magnetic clutch is connected, on the one hand, to the plate 41, and on the other hand to the terminal B_1 of the source of current. This terminal B_1 is itself connected to the electro-magnet E1.

The device described above operates in the following manner:

30 The contact 45-46 being closed, when one of the counterweights A is impelled upwards in the direction of C_1 (by depressing a key on the keyboard, not shown), its upper shoulder C_2 causes the flap 38 to swing in the direction of the arrow C_3 ; the blades 41 and 42 bear on the contacts 43 and 44. The electro-magnetic clutch device 53 is energized and the ratchet wheel caused to rotate. The electro-magnet E1 is energized and starts the perforating device described above. When the rods 1 move in the direction of F_1 (Figs. 1-2), said rods, by 35 a mechanical connection system 47a, act on the lever 47 in the direction of the arrow F_c thus opening the contact 45-46 and hence de-energizes the electro-magnet E1. By the displacement of lever 47, the pawl 50 engages a tooth of the ratchet wheel 52 which is always rotating (slow movement in the direction of F_{11}) and the lever 47 moves, first slowly in the direction of F_b , then abruptly, the pawl 50 moving away from the tooth with which it was engaged. This escaping movement may be enhanced, for example, by a pin 56 co-operating with an inclined surface 57 provided on the pawl 50. The contact 45-46 is restored and if in the meantime the counterweight A has returned to its initial position, the device is ready to work under the action of another key (or the same key) the assembly having resumed its initial position. But if the operator has kept his finger on the same key, the device works again in the manner described above, as many times as is required for reproducing the same letter. The advantage of the device according to the invention thus does not involve any change in the operator's habits and at the same time allows the repeated perforation corresponding to a required letter.

It is obvious that the counterweights A, in relation to the composing machine, play the same part that they have always played. Thus, independently of the perforations made on a tape when each key is depressed, there corresponds, as usual, the release of a matrix which goes towards making a line, and this is achieved when the keyboard is directly mounted on said composing machine.

70 It will be understood that the above-described composing machine may have associated with it a suitable apparatus, called a counter, for checking the line after the operator has depressed a certain number of keys, 75 this checking process being known in the art as "justi-

ification." Also, the keys of the composing machine, according to the present invention, may be actuated automatically by a suitable mechanism.

It will be obvious to those skilled in the art that various changes may be made without departing from the spirit of the invention and therefore the invention is not limited to what is shown in the drawings and described in the specification but only as indicated in the appended claims.

What I claim is:

1. In a conventional keyboard of a composing machine, keys mounted on lever arms, counterweights movably mounted at the end part of each lever arm of each key and comprising a plurality of banks at said lever arm side and a plurality of notches at the opposite sides, said notches being located differently from one counterweight to the other, a plurality of rods, means mounting said rods for oscillation in juxtaposition with said notches, so that at least one rod can engage in one notch of one counterweight when said counterweight is raised, two rods adapted to oscillate and which do not cooperate with said notches, a synchronization electromagnetic device, a source of electric current, a pair of electric contacts closed by each of said counterweights when the latter are raised, a flap, means movably mounting said flap adjacent said rods for engagement and movement thereby, lock means including an electromagnet for permitting movement of said flap by said rods, said electromagnet being connected to said pair of contacts and said source of electric current, a spring connected to and urging each rod in the direction of abutment against said flap, each rod having an articulated form extending therefrom, a shoulder on each arm, a plurality of segment gears each having a plurality of rollers extending from a side thereof, means mounting each said gear adjacent one of said arms for engagement of said arm with a roller of said gear upon oscillation of the rod to which said arm is attached, ratchet means mounted adjacent each said gear for engagement with a roller thereof, each said ratchet means having a part engageable by the shoulder on each corresponding arm whereby movement of said arm removes said ratchet means from engagement by one of said rollers, a plurality of continuously rotating toothed wheels, each positioned to engage and drive one of said segment gears upon initial rotation thereof by engagement of one of said arms with a roller of said gear, a bar positioned adjacent each said segment gear for striking of one end thereof by a roller of each segment gear, punch means operatively associated with each said bar for punching a tape, means for feeding a tape into juxtaposition with said punch means, and means connected with said two rods not cooperating with said notches of said counterweights for actuating said tape feeding means, whereby upon the depressing of a key a counterweight will be raised, the electromagnet will be energized, said two rods not cooperating with the notches of the counterweights will be oscillated, at least one of the other rods will be oscillated and will thereby initially rotate the corresponding segment gear, a punch means will be actuated to perforate a tape and the tape feeding means will be actuated to feed a tape.

2. In a conventional keyboard of a composing machine, keys mounted on lever arms, counterweights movably mounted at the end part of each lever arm of each key and comprising a plurality of banks at said lever arm side and a plurality of notches at the opposite side, said notches being located differently from one counterweight to the other, a plurality of rods, means mounting said rods for oscillation in juxtaposition with said notches, so that at least one rod can engage in one notch
